UNITED STATES PATENT OFFICE.

FERDINAND H. HEINE, OF MILWAUKEE, WISCONSIN, ASSIGNOR TO KOEHRING COMPANY, OF MILWAUKEE, WISCONSIN.

TRACTION SHOE.

Application filed December 19, 1921. Serial No. 523,515.

To all whom it may concern:

Be it known that I, FERDINAND H. HEINE, citizen of the United States, residing at Milwaukee, in the county of Milwaukee and State of Wisconsin, have invented certain new and useful Improvements in Traction Shoes, of which the following is a specification.

The present invention has to do with traction devices of the endless type, and useful for sustaining the weight or load of large bodies, such as machines, and rendering the latter portable when the traction devices are operated.

Such traction devices are made up of a plurality of shoes connected together and forming a sort of endless chain or belt passing around tumblers or sprocket wheels. This invention comprises a special construction of shoe designed with a view particularly to obtaining an exceedingly light structure but one having a maximum of strength and rigidity. In the carrying out of the invention, I utilize a cast body for the shoe, cored out beneath the same to render it light in weight, a covering plate being applied to the bottom of the body and the cored out portions being strengthened by webs or ribs reinforcing the plate or covering member against inward displacement. The body is so made as to provide a driving lug or tooth centrally thereof, relatively staggered pivot lugs at certain opposite edges for pivotally connecting the sections of shoes together, and a flat inner or top surface forming tracks or ways with which certain bearing rollers, forming a part of the traction unit, are adapted to engage.

The preferred exemplification of my invention is illustrated in the appended drawings, in which:

Figure 1 is a top plan view of one of my shoes.

Figure 2 is an end elevation.

Figure 3 is a side elevation of two of the shoes in connected relation, one of them being broken away and shown in section to bring out its hollow body construction.

Figure 4 is a perspective view of the bottom tread plate or closure.

Specifically describing my invention, it is notable that my shoe is of very simple construction. The body 1 of the shoe is trans-

versely elongated and is provided at its front and rear edges with the pivot lugs 2. 55 These lugs are staggered in respect to the relation of those upon one edge and those on the other edge of the shoe, as seen best in Figure 1. Centrally of the body 1 is the driving lug or tooth 3, the same being 60 of somewhat tapered construction and being adapted to fit between driving portions of a tumbler or driving wheel, not illustrated.

Portions of the top or inner surface of 65 the shoe at opposite sides of the lug 3, and designated 4, are relatively flat and form tracks with which are adapted to engage bearing rollers and bearing surfaces of the tumblers, the said rollers also not being 70 illustrated.

At opposite transverse extremities of the shoe the body is slightly curved upwards from the bottom or outer side, as shown at 5. The said body 1 of the shoe is largely 75 of hollow formation as shown at 6 and likewise the lug 3 is hollow as shown at 7. This construction is designed to make for lightness and economy of metal. Transverse webs 8 and longitudinal webs 9 separate 80 the hollow portion of the shoe into a number of different chambers or cavities and accomplish the additional function of rendering strong and substantial the hollow construction utilized for said body. 85

In order to prevent dirt and other foreign matter from entering the body 1, and to provide a flat tread surface for the shoe, a tread plate 10 is applied to the outer or bottom portion of the shoe so as to cover the cavities 90 or chambers at 6 and 7, and suitable screws, rivets or like fastenings shown at 11 pass through the body of the shoe and through the plate 10 firmly uniting these parts together. 95

Structurally speaking, the design of the shoe as presented above affords a stout body and top compression member, plate 10 constituting a tension member, and the whole structure as a unit is one employing 100 a minimum of material and having a maximum of strength and lightness. On this account the cost of the shoe as an article of manufacture is reduced materially in the making thereof, and since the cavities 6 105 and 7 and the holes for the fastenings 11 are

cored, there is no machine work necessary upon the unit. As shown in Figure 3 several shoes are assembled with a pintle or hinge pin 12 connecting them at the front 5 and rear ends, so that the shoes are quite flexible, something necessary in order that they may constitute a flexible traction unit once assembled. Furthermore, the pivot lugs 2 fit snugly together and do not allow 10 material dropping upon the traction devices to pass therethrough. The webs 8 and 9 reinforce the plate 10 effectively, being engaged with the inner side of the latter as will be obvious from the drawings. At the 15 side extremities of the shoe the openings for the fastenings 11 are somewhat inclined for obvious reasons.

The pivot lugs 2 are so arranged that the shoe is interchangeable so far as its connections with adjacent shoes are concerned; 20 that is it makes no difference which set of lugs, either those at one edge of the shoe or the other, are presented for connection to the next shoe, so long as the shoe of course 25 is right side up.

Having thus described my invention, what I claim as new and desire to secure by Letters Patent is:

1. A traction shoe comprising a relatively 30 narrow long body having at its front and rear edges pivot lugs integral therewith, said body being closed at its inner or upper portion and of hollow formation so that it is open at its lower portion, and the 35 pivot lugs being substantially in the plane of the body, the said inner or upper portion of the body being formed with downwardly extending reinforcing webs having a vertical arrangement and terminating adjacent to the open lowermost portion of 40 said body, and a cover plate attached to the body and of relatively thin formation and arranged so as to close the open lower portion of the body and to abut with the 45 reinforcing webs as to be braced by the latter, and the body being equipped with a driving member to co-operate with a driving tumbler or sprocket.

2. A traction shoe comprising a relatively 50 narrow long body having at its front and rear edges pivot lugs integral therewith, said body being closed at its inner or upper portion and of hollow formation so that it is open at its lower portion, the said inner or 55 upper portion of the body being formed with downwardly extending reinforcing webs having a vertical arrangement and terminating adjacent to the open lowermost portion of said body, and a cover plate attached to the body and of relatively thin formation 60 and arranged so as to close the open lower portion of the body and to abut with the reinforcing webs as to be braced by the latter, the said body at its upper closed 65 portion being formed with an integral up-

wardly or inwardly extending lug of hollow formation and reinforced by one of the reinforcing webs aforesaid and having its hollow portion leading into the hollow portion of the body.

3. A traction shoe of the class described, comprising a hollow body, a separate cover plate attached to and covering the hollow portion of said body, together with driving means for the body, and webs within the body reinforcing the same and reinforcing the cover plate against inward displacement.

4. As a new article of manufacture, a traction shoe composed of a hollow body in the hollow portion of which are webs, 80 a hollow driving lug extending from the inner side of the body with its hollow portion forming a continuation of the hollow portion of the body, and a cover plate secured to and covering the hollow portion of 85 the body, together with means for pivotally connecting the shoe with an adjacent similar shoe.

5. As an article of manufacture, a traction shoe comprising a body of hollow formation 90 provided with a hollow driving lug extending from the inner side thereof, the hollow portion of the body being closed upon the side equipped with the driving lug and open at the opposite side.

6. As an article of manufacture, a traction shoe comprising a body of hollow formation provided with a hollow driving lug extending from the inner side thereof, the hollow portion of the body being closed upon the side equipped with the driving lug and open at the opposite side, and a cover plate attached to the bottom of the shoe and extending over the open side of the body and forming a tread member closing said open 105 side.

7. As an article of manufacture, a traction shoe comprising a body of hollow formation provided with a hollow driving lug extending from the inner side thereof, the hollow portion of the body being closed upon the side equipped with the driving lug and open at the opposite side, and a cover plate attached to the shoe and extending over the open side of the body and forming a tread member, the body being formed internally 110 with bracing webs intermediate its closed side and said plate.

8. As an article of manufacture, a traction shoe comprising a body of hollow formation provided with a hollow driving lug extending from the inner side thereof, the hollow portion of the body being closed upon the side equipped with the driving lug and open at the opposite side, and a cover plate attached to and extending over the open side of the body and forming a tread member, the body being formed internally with bracing webs intermediate its closed side and said plate, one of the webs extending in 120 125 130

the hollow lug to brace the same, and the front and rear edges of the body being equipped with offstanding pivot lugs.

9. As a new article of manufacture, a traction shoe consisting of a hollow casting forming a body closed at the upper or inner side thereof, and open at the lower portion thereof, said upper or inner side being formed with an integral inwardly and upwardly extending hollow lug, the hollow portion of which leads from the hollow portion of the body, said body casting having integral lugs at its front and rear edges for connection with the lugs of a complementary shoe, and the body and said lugs being in substantially the same plane, a cover plate for the open lower portion of this shoe, and the body being provided internally at intervals with reinforcing webs one of which enters the hollow lug.
10. As a new article of manufacture, a traction shoe consisting of a hollow casting forming a body closed at the upper or inner side thereof, and open at the lower portion thereof, said upper or inner side being formed with an integral inwardly and upwardly extending hollow lug, the hollow portion of which leads from the hollow portion of the body, said body casting having integral lugs at its front and rear edges for connection with the lugs of a complementary shoe, and the body and said lugs being in substantially the same plane, opposite ends of the body being slightly up-curved, and the body being provided internally at intervals with reinforcing webs one of which enters the hollow lug.

10. As a new article of manufacture, a traction shoe consisting of a hollow

casting forming a body closed at the upper or inner side thereof, and open at the lower portion thereof, said upper or inner side being formed with an integral inwardly and upwardly extending hollow lug, the hollow portion of which leads from the hollow portion of the body, said body casting having integral lugs at its front and rear edges for connection with the lugs of a complementary shoe, and the body and said lugs being in substantially the same plane, a cover plate for the open lower portion of this shoe, and the body being provided internally at intervals with reinforcing webs one of which enters the hollow lug, and fastenings passing thru the body at said reinforcing webs and securing the cover plate in place on the body so that it provides a smooth tread surface for the body.

In testimony whereof I affix my signature.

FERDINAND H. HEINE.
